Primary Examiner — Kevin Rudzinski(74) *Attorney, Agent, or Firm* — Ladas & Parry LLP(57) **CLAIM**

We claim the ornamental design for a TV display screen displaying GUI, as shown and described.

DESCRIPTION

The FIGURE is a front side view of a TV display screen displaying GUI showing our new design. The broken lines shown in the drawing illustrate portions of the TV, display screen and GUI that form no part of the claimed design.
